UNITED STATES PATENT OFFICE

HENRY H. LOGAN, OF CHICAGO, ILLINOIS

CONFECTION DISPLAY DEVICE

Application filed March 28, 1931. Serial No. 525,929.

The present invention relates to confection display devices and is particularly concerned with devices for displaying confections which may simulate the appearance of building materials such as brick and mortar.

One of the objects of the invention is the provision of a novel confection display device which is adapted to increase the sales of confections.

10 Another object of the invention is the provision of an improved confection display device which will appeal to young and old alike and which will attract the attention of purchasers.

15 Another object is the provision of an improved confection display device of the class described which is collapsible so that the devices may be conveniently folded and shipped and kept in stock by confectioners 20 in a minimum of space.

Another object is the provision of an improved article which is adapted to be used as place cards or favors at banquets or other festive occasions where builders, masons, contractors or material men may be present.

25 Another object is the provision of an improved confection display device which is simple, economical, novel in appearance and construction, and capable of enhancing the sales value of confection at a minimum addition in cost.

Other objects and advantages of the invention will be apparent from the following description and from the accompanying 35 drawing, in which similar characters of reference indicate similar parts throughout the several views.

Referring to the drawing,

Fig. 1 is a view in perspective of one of the preferred embodiments of my confection display device.

Fig. 2 is a fragmentary view of a modification displaying a different kind of confection.

45 Fig. 3 is a plan view of the hod in collapsible position.

The present display device may be made of card board or paper having the requisite amount of stiffness, tin, or any sheet material 50 capable of being used for the same purpose.

The device is preferably constructed of relatively stiff paper or card board and preferably includes a miniature hod indicated in its entirety by the numeral 10 in Fig. 1, and a miniature hod supporting device 11. The hod may be formed of a blank having the shape shown in Fig. 3, in which a blank of paper having the requisite stiffness is provided with a crease or fold 12 extending longitudinally down the middle of the blank and separating the blank into a pair of folds 13 and 14 which are adapted to serve as the sides of the hod. The right ends of the sides 13 and 14 are curved at 15, 16 to simulate a hod of round shape at the open end, although the square shape may be utilized if desired.

The opposite end of one of the folds such as the fold 13 may carry an additional fold 17 which is joined to the fold 13 along the line 18, and which is adapted to serve as the end of the hod. The end of the hod preferably carries an attaching flange 19 provided with a tab 20 which is joined to the end fold 17 along the line 21. The fold 14 may be provided with a pair of slots 22, 23 adapted to receive the tab 20 and secure the parts of the hod in the position of Fig. 1, but if desired the tab 20 may be eliminated and the flange 19 secured directly to fold 14 by a metallic clip 24, 25 of the type shown at 24, 25 in Fig. 1.

The handle 26 comprises a pair of folds 27, 28 formed by folding a strip longitudinally upon itself along a line 29 midway between the edges of the strip and the strip is preferably split along the line 29 to the point 30, thereby forming two forked ends 31 for the handle. The ends 31 of the handle may be secured by metallic clips 32 to the sides 13, 14 of the hod and when it is desired to collapse the hod the body of the handle 26 may be folded down against either of the ends 31 and against the side 13 or 14 as shown in Fig. 3.

The hod blank shown in Fig. 3 may be formed into the hod of Fig. 1 by folding the sides 13 and 14 along the line 12 and bringing them into the position shown in Fig. 1 with the flap 19 on the inside of the fold 14. The tab 20 should be passed out through the slot 106

22 and in the sotl 23 thereby holding the hod in assembled position.

The hod may be filled with a plurality of blocks 33 of confection, the blocks being red in color like ordinary bricks or taking variegated colors which are employed in the various bricks used in building operations. If desired the bricks may all be of one color or of different colors to produce predetermined designs, but the blocks 33 preferably have proportions which are the same as ordinary bricks.

The bricks 33 may be retained in the hod 10 by a covering of transparent flexible material 34 such as cellophane which is folded over the bricks and pasted to the sides of the hod or which completely surrounds the body of the hod 10.

Referring to Fig. 2, the hod 10 of this embodiment is filled with a confection 35 consisting of an integral piece of confection preferably placed in the hod when initially plastic to take the form of the hod and simulate the appearance of a supply of mortar. In this case the confection may take the same color as ordinary building mortar, but since building mortars are now supplied in all colors it will be evident that this confection may be put up in attractive form in any color.

The supporting device 11 for the hod preferably comprises a collapsible member made of sheet material such as stiff paper or card board comprising a pair of plies or folds 36, 37 which may be secured together by metallic clips 24, 25 to form a relatively stiff body extending vertically and provided with a cut-out 38 at its upper end of angular shape forming a forked end of proper shape to engage the sides 13 and 14 of the hod. The lower ends of the plies 36, 37 of sheet material may be made wider to make a wider and more stable base, and may be folded along the lines 39, 40 into a plane transverse to the body of the holding device 11, thereby providing the base flaps 41, 42. The body 43 is preferably formed with cut-outs 44 oppositely located on the opposite sides of the body 43 so that the hole in the ply 36 is covered by the remaining body of the ply 37 and vice versa. The flaps 45 which are bent out over the cut-outs 44 are provided with lower edges 46 adapted to engage the base flanges 41 and 42, and to maintain the body 43 in a vertical position.

It will thus be observed that both the supporting device and the hod are capable of being folded or collapsed into compact form for shipment and storage, and the display device may be very economically constructed of stiff paper or cardboard although tin or other sheet metals may be used for more expensive embodiments of the invention. The supporting device 11 may be located beneath the hod 10 with the forked end engaging the sides 13, 14 of the hod at a point substantially midway between the ends of

the hod and the handle 26 extending vertically along the side of the supporting device 11 and engaging the body thereof. The candy thus displayed presents a very attractive and appealing form for promoting sales or for use as place cards, particularly when used by people engaged in the building trades, and the use of the present device also lends itself readily to the use of attractive sales slogans.

While I have illustrated and described a specific embodiment of my invention, many modifications may be made without departing from the spirit of the invention, and I do not wish to be limited to the precise details set forth but desire to avail myself of all changes within the scope of the appended claims.

Having thus described my invention, what I claim as new and desire to secure by Letters Patent of the United States is:

1. In a confection display device the combination of a base comprising oppositely extending flat portions of sheet material, a standard carried by said base, and comprising an upwardly extending part of sheet material at right angles to said base, said standard having a V-shaped end with edge portions extending at an angle to each other, a hod comprising a pair of sides of sheet material disposed at the same angle to each other as said V-shaped end, whereby said hod will substantially fit the end of said standard, an additional portion of said material connecting the sides of said hod and closing one end thereof, and a handle connected to the lower surface of said sides, and extending downward into engagement with said standard, said hod being proportioned to dispose the major portion of the weight on the same side of said standard as said handle to urge said handle into engagement with the side of said standard, and to support the hod in stable position on said standard.

2. A collapsible display device for confection comprising a blank of sheet material having a pair of folds adapted to serve as the sides of a hod and a third fold carried by the end of one of said first mentioned folds to serve as the end of the hod, means for securing said folds together to form a miniature hod, and a foldable handle carried by said first mentioned folds.

3. A collapsible display device for confection comprising a blank of sheet material having a pair of folds adapted to serve as the sides of a hod and a third fold carried by the end of one of said first mentioned folds to serve as the end of the hod, means for securing said folds together to form a miniature hod, and a foldable handle carried by said first mentioned folds, comprising a strip of sheet material folded upon itself longitudinally of the strip and split longitudinally,

one of each of the folds thereof being secured to the sides of said hod.

4. A collapsible confection display device comprising a piece of sheet material having a pair of plies secured together to form the body of a miniature hod supporting device, said body being formed with a fork at its upper end and said plies being bent into a plane transverse to the body of said device at the opposite end and extending in opposite directions to form a base for the same.

5. A collapsible confection display device comprising a piece of sheet material having a pair of plies secured together to form the body of a miniature hod supporting device, said body being formed with a fork at its upper end and said plies being bent into a plane transverse to the body of said device at the opposite end and extending in opposite directions to form a base for the same, said body and base being provided with a pair of cut-out flanges adapted to be bent up to a position transverse to said body and base to support said body in a vertical position with respect to said base.

6. A confection display device comprising a collapsible hod adapted to receive a predetermined amount of confection, said hod having a pair of angularly disposed sides and an end piece joining said sides, a bifurcated handle engaging the angularly disposed sides and adapted to be folded against either of said sides.

7. A supporting device for a confection display comprising a collapsible hod supporter constructed of relatively stiff sheet material, having a standard formed with a forked end to receive a hod, a base comprising oppositely extending feet and braces extending transversely to the base and standard, and adapted to hold the standard in predetermined position with respect to the base, the parts of said base being adapted to be folded together substantially into the plane of the standard.

65 In witness whereof, I hereunto subscribe my name this 24th day of March, 1931.

HENRY H. LOGAN.
